UNITED STATES PATENT OFFICE

JEFFREY JOHN WALLACE, OF AMITE, LOUISIANA, ASSIGNOR TO GULLETT GIN COMPANY, OF AMITE, LOUISIANA

GIN RIB

Application filed October 9, 1929. Serial No. 398,492.

This invention relates to cotton gins generally, and more particularly to the construction of the cotton ginning ribs, and their arrangement relative to each other and the 5 saws of the gin.

In cotton gins, as at present used, there is quite a large space between the ribs at the back thereof, and motes and foreign particles are thrown into this space by the saws, 10 and soon cause the choking of the ginning spaces between the ribs which prevents the saws from operating efficiently. This is particularly true where the saws rotate at high speed and the motes and particles are thrown 15 away from the saws by centrifugal force to the back of the ribs.

It is the main object of this invention to provide a new type of cotton ginning ribs so shaped as to prevent the choking of the ginning spaces when the ribs are properly positioned on the rib bars of the machine.

Other objects of the invention will become apparent as the detailed description thereof proceeds.

25 In the drawings:

Figure 1 is a side elevation of a ginning rib constructed according to the present invention and secured to rib bars which are shown in section taken on the line 1—1 of Figure 2, 30 the scale in Figure 1 being reduced;

Figure 2 is a front elevation showing a number of the gin ribs secured to the bars of the gin;

35 Figure 3 is a section to an enlarged scale taken on the line 3—3 of Figure 1;

Figure 4 is a similar section taken on the line 4—4 of Figure 1;

40 Figure 5 is a section taken on the line 5—5 of Figure 1;

Figure 6 is a section taken on the line 6—6 of Figure 1; and

Figure 7 is a section taken on the line 7—7 of Figure 1.

45 As shown in the drawings, the gin ribs 1 are secured, at their upper ends, by screws 2 to a bar of wood 3 suitably fixed in a channel iron 4 forming the upper gin rail. The lower ends of the gin ribs 1 are likewise secured by screws 5 to a wooden bar 6 suitably

fixed in a channel iron 7 forming the lower gin rail.

The opposite ends of each rib terminate in flat plates 8 and 9, having their outside edges 10 and 11 parallel to each other. These plates 55 8 and 9 are of the same width so that when the ribs are arranged on the rib bars, the adjacent edges of the plates may be mounted in contact with each other and will properly space the curved parts of the ribs relative to 60 each other.

At the lower part of the ribs, the spaces 12 between adjacent ribs are substantially of the same width as are the spaces of the present type cotton gins. However, in order 65 to prevent motes and foreign particles to be thrown through these spaces by the saws, the ribs 1 are gradually tapered on their adjacent edges from bottom to top, so that the spaces 13, at the points where the upper part 70 of the saws intersect the ribs, are substantially filled by the saws.

Each rib where it starts from the bottom rail, is shaped substantially as shown in Figure 5, but the width of the back thereof is 75 increased, as it rises toward the top rail, by flanges 14 and 15 extending from the lower end of the rib. Each of the said flanges becomes wider as it approaches the top rail, and is terminated a short distance from the top 80 rail as indicated by the line 16.

The bodies 17 of the ribs continue along the plate 8 to form sides 18 and 19, which form with the adjacent sides of the adjacent ribs a plurality of spaces to allow cotton 85 to escape out of the slot formed by the sides of the adjacent ribs near the top thereof.

At the point 20, where the saw 21 intersects the gin ribs, the flanges 14 and 15 are square and are wider at this point than at 90 any other point. This filling up of the spaces between the adjacent ribs prevents the motes and foreign particles from leaving the saws until the saws have carried them beyond the back of the ribs; at which point they are 95 free to be thrown from the saws without getting into the space back of the ribs.

From the line 22, passing through the points 20, the rib bodies 17 taper slightly toward their tops to allow any foreign substance 100

ready relief in escaping out of the back of the ribs. From the same line the flanges 14 and 15 are slightly tapered toward the line 16 to allow cotton to escape out of the spaces or slots 13 as the roll turns in anti-clockwise direction in the roll box.

The wood bars 3 and 6 are flush with the edges of the flanges 4 and 7, which form the rib rails of the gin. The plates 8 and 9 are fastened to these wood bars as previously described, and have their under faces in metallic contact with the adjacent flanges of the said rib rails.

In the operation of the gin, it will be evident that as the saws rotate freely through the wide spaces between the lower ends of the gin ribs, they will carry up motes and foreign particles along with them, but these motes and particles will be prevented by the flanges 14 and 15 from escaping to the back of the ribs. The motes and particles will be carried along these ribs until they reach the points 20 where the saws again intersect the ribs and will there be engaged by the teeth of the saws and thrown away from the backs of the ribs.

The inward tapering of the bodies 17 of the ribs from the points 20 toward the top thereof allows any foreign substance to escape out to the back of the ribs; and the continuation of these bodies along the plates 8 form recesses which provide additional clearances. The tapering of the flanges toward the line 16 also allows cotton to escape from the slots 13 as the roll turns in anti-clockwise rotation in the roll box of the gin.

While I have shown and described a particular embodiment of my invention, it must be understood that the invention is not to be considered as limited to the particular form shown, but extends to all construction for performing the same function and as limited only by the claims appended hereto.

What I claim is:

1. A gin rib comprising a body having flat plates at the opposite ends thereof adapted to be attached to the rib rails of the cotton gin and having an arcuate portion between said plates tapering in opposite directions from a point between the center of said portion and one of said plates, the opposite edges of the back of said body being provided with flanges which diminish in width in opposite directions from said point, the said body extending partly over the flat plate adjacent the wide end of the body, and said flanges terminating a short distance from the last named plate.

2. A gin rib tapered widthwise from an intermediate point so as to form in combination with an adjacent similar rib a saw-channel narrow adjacent the upper part of the saw edge and relatively wide adjacent the lower part of the saw edge, said rib being formed with a flat face on the roll box side

including flanges projecting laterally from the body of the rib, a rail engaging plate at the upper end of said rib, said flanges narrowing adjacent said rail to form with the adjacent rib a relatively wide cotton discharging channel on the roll box side of said rib adjacent said rail engaging plate.

In testimony whereof I affix my signature.

JEFFREY JOHN WALLACE.
